(57) CLAIM

The ornamental design for a portion of a game controller, as shown and described.

DESCRIPTION

FIG. 1 is a front perspective view of a portion of a game controller showing our new design;

FIG. 2 is a top view thereof;

FIG. 3 is a left side view thereof;

FIG. 4 is a right side view thereof;

FIG. 5 is a front view thereof;

FIG. 6 is a rear view thereof; and,

FIG. 7 is a bottom view thereof.

The broken line showing of the remainder of the game controller is for illustrative purposes only. The broken lines and unshaded regions form no part of the claimed design.

1 Claim, 4 Drawing Sheets
